UNITED STATES PATENT OFFICE.

CHARLES E. SIMPSON, OF CHICAGO, ILLINOIS.

FIRE-DOOR.

SPECIFICATION forming part of Letters Patent No. 746,885, dated December 15, 1903.

Application filed June 15, 1903. Serial No. 161,437. (No model.)

To all whom it may concern:

Be it known that I, CHARLES E. SIMPSON, a citizen of the United States, and a resident of Chicago, in the county of Cook and State of Illinois, have invented certain new and useful Improvements in Fire-Doors; and I do hereby declare that the following is a full, clear, and exact description thereof, reference being had to the accompanying drawings, and to the letters of reference marked thereon, which form a part of this specification.

This invention relates to improvements in fire-doors and, as shown, to metallic doors designed for use in divisional walls.

15 The object of the invention is to provide a fire-door of simple construction having secured thereto means for automatically closing and securely fastening the same when the temperature of the air in the room has reached 20 a predetermined degree.

The invention consists of the matters hereinafter described, and more fully pointed out and defined in the appended claims.

In the drawings, Figure 1 is a perspective view of a device embodying my invention, showing the same in its normal position. Fig. 2 is a similar view showing the automatic closing mechanism in the act of closing the door. Fig. 3 is an enlarged front elevation of the trip mechanism in its supporting position. Fig. 4 is a side elevation of the same. Fig. 5 is a front elevation of the same, showing the trip released. Fig. 6 is a side elevation of the catch for the door-latch. Fig. 7 is a view of 35 a fusible link or thermostat embodied in my invention.

As shown in my drawings, A indicates a wall of any desired material having an opening therethrough, to close which it is desired 40 to provide an automatically-closing fire-door.

As shown, said wall is of brick, and said opening is provided with a metallic frame a in a familiar manner. On one side of said frame are secured the inwardly-projecting catches a' a'', 45 rigidly secured in said frame and projecting into the room or compartment in which the door swings. On the opposite side of the frame are provided the apertured lugs a³ a⁴ a⁵, as shown, three in number and located near the 50 middle and near the top and bottom of said frame and each forming one member of the

hinge. The door is provided with an equal number of transverse straps b b' b'', which project beyond the margin of the door and are each provided with a bolt or pin adapted to 55 engage in the aperture in the corresponding lugs a³, a⁴, or a⁵ and together therewith form the hinges. Extending beyond the opposite margin of the door are the latches b³ b⁴, the outer or free ends of which are adapted to engage the catches a' a''. Said latches are desirably of considerable length and are pivoted 60 at their inner ends and connected by means of the bar or strap b⁵, the opposite ends of which are pivotally secured to the respective 65 latches in such a manner that movement in one of said latches produces a corresponding movement in the other. A handle b⁶ of any desirable form is preferably secured upon said bar or strap, whereby said latches may be 70 raised in opening the door. For the purpose of automatically closing said door in the event of fire or such a change of temperature as would indicate fire a trip mechanism is provided on one side of said door, near 75 the top thereof, comprising a base E, rigidly secured on the wall and provided at its lower end with the outwardly-projecting lugs e, between which is pivoted the trip-lever E', at 80 the lower end of which is the outwardly-projecting hook e'. The upper end of said trip-lever is provided with a relatively broad plate e², parallel with the base E when the trip-lever is in its supporting position. E² indicates an 85 apertured latch pivoted on said base, as shown in Figs. 3 and 5, and adapted to swing laterally and provided with a spring e³, which normally holds said latch in the position indicated in Fig. 3. On the rear side of said plate e² is rigidly secured the rearwardly 90 and laterally directed arm E³, having at its outer end a roller which engages on the rear side of said latch when the trip-lever is in its supporting position, as shown in Figs. 3 and 4, so that when said latch is moved laterally 95 said arm is released thereby and the trip is permitted to fall. As shown, said latch is provided with an upwardly-extending projection e⁵, which engages behind a pin e', extending parallel with the top of the base and secured 100 in a lug integral with the base. Said pin acts to support the latch against downward strain

on the trip-lever. Means are provided for releasing said trip-lever, comprising the pulleys D D', weight D², and thermostat or fusible link D³, which operate as follows: The 5 chains d d' are each secured at one end to said weight D² and pass, respectively, over the pulleys D D' and are secured to the projection e⁵ and the thermostat D³ and are respectively of such length that said weight is 10 normally supported on the chain d' and the thermostat-link alone, while the chain passing to the latch is slack. A weight F, as shown, is supported by means of the spring f and tackle-blocks c and c' on the hook e' of 15 the trip-lever. The block c, as shown, is a double block and the block c' is single, and the chain or other flexible connection C is rove therethrough, the inner end thereof being secured to the strap at the top of the 20 block c'. The other end thereof passes through sheaves c² and c³, located to lead the connection to a point above and near the middle of the door and is secured on a lug c⁷, rigidly secured on the door. The inner end 25 of the supporting-chain is moved upwardly, as shown in Fig. 1, to form a bight which is passed over the hook e' of the tripping-lever. As shown, an enlarged ring or link is secured in said chain at said point to afford better 30 means for engaging said hook. As shown, said weight F, the tackle therefor, and the trip mechanism are inclosed in a box or casting to protect the same from injury. The weight F is about a third heavier than sufficient 35 to close the door when suspended over the sheave c². As shown in Fig. 1, however, the same being supported on three strands of the line or chain, two of which lead to the trip mechanism, less than one-third of the 40 gravity of the weight is effective on the door, which is insufficient to close it, and as a result the door will remain in any position in which it may be placed, either open or closed. The door being open and the temperature 45 having risen to a point sufficient to fuse the link D³, the weight D² falls, jerking upon the chain d, and pulls the latch E² laterally against the action of the spring e³ to the position shown in Fig. 5, thereby releasing the upper 50 end of the trip-lever. Inasmuch as the hook e' projects forwardly out of alignment with its pivot, the gravity of the weight F and the tackle c and c' of the chains pulls the trip-lever downwardly until the bight of the chain 55 slips from said hook, whereupon the weight F and tackle-blocks fall to the position indicated in Fig. 2 and jerk violently upon the chain. The entire weight now supported upon the single strand being a third more 60 than sufficient to close the door, the door swings quickly to its closed position. The latches b³ b⁴ engage over the catches a' and a² and permanently lock the door in its closed position until the same is manually opened. 65 It frequently happens that fire-doors are secured one on each side of the wall, in which case an air-cushion is sometimes formed be-

tween said doors as they close, which in ordinary construction acts to resist the closing of one or both of the doors. The spring f 70 aids in effectively closing against such air-cushion, inasmuch as it causes the weight to vibrate up and down, giving a succession of jerks on the chain, said successive impulse aiding materially in closing the door. 75

As a further improvement I have so constructed the catches a' a² that the upper latch b³, which is close to the point of attachment with the chain, engages on the catch a' before the latch b⁴ engages on the catch a². 80 For this purpose said catch a' is constructed longer than the catch a², and the upper surface thereof is provided with a gradual slope or inclination, so that when the latch b³ engages thereon the latch b⁴ is supported above 85 the catch a², as shown in Fig. 2, and only engages the same when both latches drop into the respective notches in said catches.

Obviously other forms of tripping devices may be employed, if preferred, than those 90 herein described and other form of construction of fusible link or thermostat may be embodied in my invention. The tripping means may be actuated by any familiar means to permit the descent of the weight F. So, too, 95 if preferred, sliding doors may be employed instead of a hinged door with the same effect and for the same purpose, and floor-openings, as well as openings in side divisional walls, may be closed by doors operated in accordance with my invention. 100

Many details of construction may be varied without departing from the principle of my invention.

I claim as my invention— 105

1. In an automatic closing device for doors and the like a weight normally supported, partly on a door and partly on a trip mechanism, by means of a spring, and when so supported insufficient to close the door, and thermally operated means to release said trip mechanism whereby said weight is supported wholly on said door and in falling exerts a plurality of impulses. 115

2. A closing mechanism for doors and the like comprising a flexible connection, engaged at one end upon the door and at the other upon a trip mechanism, a weight supported on said flexible connection and normally in position to close the door, a fusible link, a flexible connection between said link and said trip mechanism, a weight supported thereon normally free from said trip mechanism and adapted when the link is fused to actuate the trip mechanism and release the aforesaid weight 120 and close said door. 125

3. A closing mechanism for doors and the like, comprising in combination, a trip mechanism, a weight, a flexible connection, reeved about a tackle suspended from the trip mechanism and attached at one end to the door, a weight secured by a spring to the lowermost block of said tackle, automatic means for releasing said trip mechanism and permitting 130

the weights to fall, thereby exerting the entire gravity thereof upon the door and acting to close the same.

4. A self-closing mechanism for doors or the like comprising a trip mechanism, a weight supported normally free therefrom, a fusible link connected therewith, a flexible connection rigidly secured at one end upon the door and at the other detachably engaged on trip mechanism, a weight movably supported thereon normally partly from the door and partly from the trip mechanism and adapted when said link is fused to exert its full weight upon the door and means for breaking the impact of the fall of said weight.

5. In a device of the class described a trip mechanism, a flexible connection detachably engaged at one end on said trip mechanism

and rigidly engaged at the other on the door to be closed, a plurality of blocks on said flexible connection, a spring-supported weight on one of said blocks, a fusible link, a flexible connection between said link and said trip mechanism and a weight thereon normally supported upon the fusible link and adapted when said link is fused to release the trip mechanism and allow the first-named weight to fall and close said door.

In testimony whereof I have hereunto subscribed my name in the presence of two subscribing witnesses.

CHARLES E. SIMPSON.
